COMBINED LAMP AND RADIO RECEIVING
SET

Daniel J. Crowley, Grosse Pointe, Mich.

Application April 12, 1938, Serial No. 201,634

9 Claims. (CL. 250—14)

This invention is a continuation in part of my Patent No. 2,176,667, dated Oct. 17, 1939, and relates to a combined article of furniture and radio receiving set.

More particularly, the invention concerns itself with a lamp constructed to embody the various instrumentalities of a complete radio receiving apparatus and has as one of its objects to provide a lamp construction having a base assembly adapted to house certain of the parts of a radio receiving set and having a shade assembly fashioned to house certain cooperating parts of the radio receiving apparatus.

In accordance with the present invention, the shade assembly is supported from the base assembly by a pedestal and it is a further object of this invention to provide means supported on the pedestal in a position to be conveniently accessible for manipulation by the operator to tune the receiving set to any one of the sending stations broadcasting on the selected wave band.

A further advantageous feature of the present invention consists in the provision of a combined lamp and radio receiving set of the type previously set forth wherein the instrumentalities of the radio receiving circuit are ingeniously arranged in compact groups distributed in different portions of the lamp in a manner to not only permit artistically proportioning the various sections of the lamp, but to also insure obtaining maximum efficiency of operation from the particular radio circuit selected.

The foregoing, as well as other objects, will be made more apparent as this description proceeds, especially when considered in connection with the accompanying drawings, wherein:

Figure 1 is a side elevational view, partly in section, of a combined floor lamp and radio receiving apparatus;

Figure 2 is a cross sectional view taken substantially on the plane indicated by the line 2—2 of Figure 1;

Figure 3 is a cross sectional view taken substantially on the plane indicated by the line 3—3 of Figure 1;

Figure 4 is a vertical sectional view through the tuning unit;

Figure 5 illustrates a diagram of one type of radio receiving circuit that may be employed in the lamp construction featured in Figure 1;

Figure 6 is a side elevational view, partly in section, of another embodiment of this invention; and

Figure 7 is a side elevational view, partly in

section, of a further modification of the present invention.

Referring first to the embodiment of the invention shown in Figures 1 to 4, inclusive, it will be noted that there is illustrated in Figure 1 a floor lamp of artistic design having a base assembly 10 and a shade assembly 11 supported from the base by means of a pedestal 12. In the present instance, a number of the instrumentalities of the radio receiving circuit are compactly distributed in the base assembly 10 and the cooperating parts of the circuit are grouped in the shade assembly 11. The several parts of the radio receiving set in the base assembly 10 are electrically connected to the cooperating parts of the circuit in the shade assembly 11 by means of electrical conductors (not shown) but which may be extended through the hollow pedestal. Although the electrical connections are not shown herein, it will, of course, be understood that the conductors must be properly shielded in accordance with radio practice to insure efficient performance of the receiving set.

Although it is to be understood that the specific parts of the radio receiving circuit housed by the above named assemblies in the lamp may vary to suit existing conditions, nevertheless, for the purpose of illustration, I have selected the following distribution of the parts. Upon reference to Figure 5, it will be noted that the radio receiving circuit selected herein for the purpose of illustrating the present invention is of the superheterodyne type. The parts of the circuit contained in the area designated by the reference character A in Figure 5 are housed in the base assembly 10 of the lamp, and the parts of the circuit contained in the area designated by the reference character B are located in the lamp assembly 11 of the lamp. In other words, the speaker unit 13 containing the instrumentalities in area B and the combined volume and "off" and "on" switch 14 are housed in the shade assembly 11, while all of the remaining instrumentalities of the circuit are grouped in the base assembly 10.

The base assembly 10 comprises a supporting plate 15 and a cover 16 detachably secured to the supporting plate by means of the fastener elements 19. The supporting plate 15 is of sufficient size to support the instrumentalities of the radio circuit contained in area A in Figure 5 and the cover 16 serves to conceal all of these parts of the radio receiving circuit. Upon reference to Figure 2, it will be noted that the various parts of the radio receiving circuit in the base assem-

bly 10 are supported on a spider 17 having a hub in the form of an inverted cup-shaped member 18. The cup-shaped member 18 is secured to the supporting plate 15 centrally of the latter by means of the fastener elements 19 and serves as a support for the lower end of the pedestal 20.

Referring again to Figure 2 of the drawings, it will be noted that the spider 17 is provided with three symmetrically arranged radially extending plates or spokes 21 and each of these spokes forms a support for a variable condenser 22. The variable condensers 22 are of conventional construction comprising the usual stator 23 and rotor 24. The blades on the stators of the variable condensers, of course, cooperate with the blades on the rotors to vary the capacitance of the circuit and tune the radio set to any one of the wave lengths on the selected band. Upon reference to Figure 1, it will be noted that the rotor shafts 25 of the several condensers are adjusted to vary the capacitance of the circuit by a central driving gear 26 rotatably mounted on the inverted cup-shaped member 18 and supported on the spider 17. The upper ends of the rotor shafts 25 are symmetrically arranged with respect to the axis of the driving gear 26 and each of the rotor shafts has a pinion 27 secured to the upper end thereof in intermeshing relationship with the driving gear 26. Thus, rotation of the central driving gear 26 effects a corresponding adjustment of each of the several variable condensers.

Rotation of the driving gear 26 to effect adjustment of the variable condensers is accomplished by means of a tuning unit 28 supported on the pedestal 12 at a point between the base and shade assemblies. The point of location of the tuning unit is predetermined to provide for convenient manipulation by the operator. The tuning unit is operatively connected to the driving gear 26 by means of a tube 29 rotatably mounted on the pedestal tube 20 in concentric relation thereto and having an inverted cup-shaped member 30 secured to the lower end thereof. The inverted cup-shaped member 30 extends through a central opening 31 in the cover 16 and the periphery of the annular side flange 32 rests upon the driving gear 26. As shown in Figure 1, the periphery of the annular flange 32 is fashioned with circumferentially spaced notches 33 adapted to receive projections 34 struck out from a ring 35 fixed to the top surface of the driving gear 26. The construction is such as to provide a readily detachable driving connection between the tube 29 and the driving gear 26.

It follows from the above that rotation of the tube 29 imparts a corresponding rotation to the driving gear 26 and, through the pinions 27, operates the variable condensers 22. The tube 29 is rotated by means of a control disc 36 shown in Figure 4 as centrally apertured to receive the pedestal tube 20 and to also receive a collar 37. The collar 37 is rotatably mounted on the tube 20 and is provided with a slot 38 of sufficient dimension to receive a projection 39 on the control disc 36. The construction is such as to provide a driving connection between the control disc 36 and the collar 37 so that rotation of the former effects a corresponding rotation of the latter. The control disc 36 is positioned axially with respect to the collar 37 by means of washers 40 and 41 threaded on the collar at opposite sides of the control disc.

The collar 37 is operatively connected to the upper end of the tube 29 by speed reducing mechanism in order to provide a vernier adjustment

of the variable condensers. In the present instance, the speed reducing mechanism is of the friction type having a plurality of freely rotatable discs 42 spaced from each other equal distances around the collar 37 and journaled on vertically extending stub shafts 43. Upon reference to Figure 4, it will be noted that the stub shafts 43 are supported on a carrier disc 44 freely rotatably mounted on the collar 37 between the radially outwardly extending flange 45 on the collar and a plate 46. The plate 46 is, of course, centrally apertured to receive the lower end of the collar 37 and this plate is supported on the collar by means of a disc 47 secured to the plate, as at 48, and has a hub 49 secured to the pedestal tube 20.

It will be noted from Figure 4 that the sides of the revoluble discs 42, adjacent the axis of the tube 20, are frictionally urged into engagement with the upper side of the radially outwardly extending flange 45 on the collar 37 by means of a disc 49 supported on the collar 37 above the revoluble discs 42 and normally urged into engagement with the latter by means of a spring washer 50. Peripheral portions of the spring washers are fashioned to provide spring fingers 51 adapted to be compressed by engagement with the washers 41 supporting the control disc 36 on the collar. As a result of the above construction, the inner sides of the revoluble discs 42 are yieldably clamped between the radially outwardly extending flange 45 and the disc 49. Referring again to Figure 4, it will be apparent that the outer sides of the revoluble discs 42 are yieldably clamped between the two rings 52 and 53. The top ring 52 is provided at spaced points with depending strips 54 secured to correspondingly spaced projections 55 extending downwardly from the plate 46. The opposed ring 53 is supported upon a plurality of spring fingers 56 struck out from the plate 46 at points spaced around the axis of the collar 37. With this construction, it will be noted that rotation of the control disc 36 by the operator exerts a driving force upon the inner sides of the revoluble discs 42 tending to rotate the carrier 44 at a corresponding rate. In the event the carrier is rotated as a unit with the control disc 36, the outer sides of the discs 42 must move through a greater arc than the inner sides, and this movement is restricted by the frictional engagement of the rings 52 and 53 with the outer sides of the discs. As a result, the discs 42 are rotated upon actuation of the control disc 36 and the carrier 44 is revolved at a much slower rate than the control disc 36. The speed differentiation, of course, depends upon the dimensions of the parts and, in the present instance, is such as to provide the desired vernier control of the variable condensers. In this connection, it will be noted that the carrier disc 44 is connected to the upper end of the tube 29 for rotating the latter at the reduced rate by means of a driving disc 57 secured to the upper ends of the shafts 43 by means of the screws 58 and having tongues 59 extending into notches 60 formed in the upper edge of a ring 61 carried by a cup-shaped cover 62. Referring again to Figure 4, it will be noted that the ring 61 is fixed to the inner surface of the upstanding flange on the cup-shaped cover 62 and the latter is secured to the upper end of the tube 29 by means of a collar 63. The cup-shaped cover 62 is of sufficient dimension to house the reduction

mechanism and to thoroughly conceal the latter from view.

One side of the cup-shaped cover 62 is provided with a slot 64 therethrough for exposing the wave indicating band 65 which is secured to the inner side of the upstanding flange of the cup-shaped cover opposite the slot. Thus, it will be seen that the wave indicating band rotates as a unit with the cup-shaped cover 62 at a reduced rate effected by the reduction mechanism, and the graduations on the wave indicating band are identified by means of a fixed pointer 66 secured to the ring 52 in the cup-shaped cover and projecting through a slot 67 in the cover 62. The slot 67 is of sufficient length to cover the entire band without interfering with the rotation of the cover 62.

In addition to the foregoing, the tuning control unit 28 is provided with means for varying the resistance controlling the volume and for also operating the switch in the supply circuit. The combined volume control rheostat and "off" and "on" switch 14 has previously been described as mounted in the shade assembly and in accordance with the present invention may be operated from a position immediately adjacent the control disc 36. In detail, a tube 70 is telescopically engaged with the portion of the pedestal tube 20 extending beyond the tuning unit 28, and the lower end of the tube 70 is provided with an enlargement 71 shaped to cooperate with the cup-shaped cover 62 in providing an attractive design. Actually, the enlargement serves as a control for rotating the tube 70 relative to the pedestal tube 20.

Upon reference to Figure 1, it will be noted that the internal diameter of the tube 70 is greater than the outside diameter of the tube 20 and the former tube is axially positioned relative to the latter tube by means of an annular projection 72 extending inwardly from the tube 70 adjacent the lower end thereof and adapted to rest upon an annular projection 73 extending outwardly from the pedestal tube 20. The ends of the cooperating projections are flat in an axial direction in order to provide an efficient bearing engagement between the two tubes.

The upper end of the tube 70 is secured to a cup-shaped member 74 in the shade assembly of sufficient diameter to receive the lower end of a housing 75, and a ring gear 76 is secured to the inner side wall of the cup-shaped member in a manner to mesh with a pinion 77 secured to the lower end of a vertical shaft 78. The vertical shaft 78 and pinion 77 are located within the housing 75 and the latter is slotted, as at 79, to provide for extending the periphery of the pinion through the side wall of the housing into engagement with the ring gear 76. As a result, rotation of the ring gear 76 by the cup-shaped member 74 and tube 70 effects a rotation of the vertical shaft 78. The upper end of the vertical shaft 78 is connected to the combined volume rheostat and "off" and "on" switch 14 in a manner to control the supply circuit to the radio receiving apparatus and to regulate the volume of the radio circuit. It follows from the above that the various instrumentalities of the radio receiving circuit requiring adjustment may be controlled from the unit 28 which is supported on the pedestal in a convenient position for manipulation by the operator.

Reference has briefly been made above to the fact that the speaker unit 13 is housed in the lamp assembly 16, together with the combined

volume rheostat and "off" and "on" switch 14. In the present instance, the speaker and power transformer are secured in any suitable manner (not shown) in the housing 75 and the latter, in turn, supports the speaker cone 80 at the upper end thereof. The housing also forms a support for the audio tube 81 and rectifier tube 82 which are connected in the radio receiving circuit in the manner clearly indicated in Figure 5. In the present instance, the illuminating electric light bulbs 83 are also supported on the housing 75 and are so positioned with respect to the other instrumentalities of the speaker unit as to prevent the latter from casting shadows. The speaker unit 13 and illuminating means are enclosed by a shade 85 positioned on the upper end of the housing and having a top wall 86 forming a baffle for the speaker.

In some installations, it may be desirable to provide the radio receiving apparatus with a tone control in association with the speaker unit. The embodiment of the invention illustrated in Figure 6 is provided with a tone control and the latter, together with the variable condensers and combined volume rheostat and "off" and "on" switch, are actuated from a control unit 90 positioned on the pedestal in substantially the same manner as the control unit 28. The variable condensers in this embodiment of the invention are actuated from the control unit 90 in exactly the same manner as defined in connection with the embodiment of the invention illustrated in Figures 1 to 5, inclusive. In Figure 6, however, the combined volume rheostat and "off" and "on" switch 91 is supported in the base assembly of the lamp. As shown in Figure 6, the device 91 is secured to the inverted cup-shaped member 18 directly below the lower end of the pedestal tube 20 in a manner to permit directly connecting the same with the lower end of an operating rod 93 extending vertically in the pedestal tube 20. The rod 93 is rotated to actuate the device 91 by means of a control 94 having a hub 95 rotatably supported on the pedestal tube 20 and having a ring gear 96 embedded therein in a manner to mesh with a pinion 97 fixed to the upper end of the rod 93. The pedestal tube 20 is formed with a slot 98 opposite the ring gear 96, and this slot is of sufficient dimension to permit the periphery of the pinion 97 to extend through the tube into intermeshing engagement with the ring gear.

The tone control for the speaker is located in the transformer housing 75 and is controlled by means of a tube 99 telescopically engaging the pedestal tube 20 above the control 90. The lower end of the tube 99 is supported on the pedestal tube 20 in the same manner as the tube 70 in Figure 1 is supported on the pedestal, and the upper end of the tube 99 is provided with a cup-shaped member 100 identical in construction to the cup-shaped member 74 in that it is provided with a ring gear 101 for rotating the pinion 102 on the tone control shaft 103. Thus, it will be noted that the construction shown in Figure 6 embodies all of the advantages of the construction featured in Figures 1 to 5, inclusive, with the additional advantage that the tone control may be operated from the control unit 90.

In the embodiment of the invention shown in Figure 7, I have illustrated the manner in which a radio receiving set may be incorporated in a table lamp. The distribution of the various instrumentalities of the radio receiving circuit may be identical to the arrangement shown in Fig-

ures 1 to 5, inclusive, and the various parts of the radio circuit requiring adjustment are controlled from a unit 105 identical to the unit 28, with the exception that it is positioned immediately adjacent the cover 106 of the base assembly. In all other respects, the construction and operation of the embodiment shown in Figure 7 are the same as the one described in detail in Figures 1 to 5, inclusive.

What I claim as my invention is:

1. In a combined lamp and radio receiving apparatus, the combination of a lamp having a base section, a shade section, a vertical stanchion supporting the shade section from the base section and including axially aligned tubes supported for rotation about the axis of the stanchion, a radio receiving circuit having parts supported within said sections of the lamp and certain of the parts being adjustable, an operative connection between one tube and one of the adjustable parts effective to adjust the latter upon rotation of said tube, an operative connection between the second tube and another of the adjustable parts effective to adjust the latter upon rotation of the second tube, and a control supported between the adjacent ends of the tubes for rotation about the vertical axis of the stanchion and operatively connected to one of the tubes through the medium of reduction mechanism for rotating the latter tube at a reduced rate.

2. In a combined lamp and radio receiving apparatus, the combination of a lamp having a base section, a shade section, a vertical stanchion supporting the shade section from the base section and including a pair of vertically aligned tubes supported for rotation about the vertical axis of the stanchion, a radio receiving circuit having parts supported within said sections of the lamp and certain of the parts being adjustable, means operatively connecting one tube with one of the adjustable parts effective to adjust the latter part upon rotation of said tube, means operatively connecting the second tube to another of the adjustable parts for actuating the latter, and means supported between the adjacent ends of the tubes for rotation about the vertical axis and operatively connected to still another of the adjustable parts for actuating the same.

3. In a floor lamp radio structure, a base, a radio set including a volume control means and a tuning control means all contained within said base, a hollow standard extending upwardly from said base for the support of a lamp shade adapted to contain a lighting means, annular dial members concentric with and independently turnably mounted on the exterior of said standard in spaced relation one above the other to occupy a location on said standard intermediate the base and the supported lamp shade, a tubular shaft to extend downwardly from the lowermost dial member into said base, a second shaft extending downwardly through said tubular shaft from the uppermost dial member and beyond the lower end of said tubular shaft into said base, transmission means between said tubular shaft and said lowermost dial member, and means connecting the lower ends of said tubular shaft and said second shaft in actuating relation one to said volume control means and the other to said tuning control means.

4. In a combined lamp and radio receiving apparatus, the combination of a base section having a pedestal extending upwardly therefrom and a shade section supported on the pedestal at the upper end of the latter, radio receiving ap-

paratus supported in the base section and including a variable condenser, an annular dial member concentric with and rotatably supported on the exterior of the pedestal at a point intermediate the base and shade sections, a shaft extending downwardly from the dial member toward the base and having the upper end operatively connected to the dial member, and means at the lower end of the shaft operatively connected to the variable condenser for actuating the same.

5. In a combined lamp and radio receiving apparatus, the combination of a base having a pedestal extending upwardly therefrom and a shade section supported on the pedestal at the upper end thereof, radio receiving apparatus supported in the base section and including a plurality of variable condensers distributed in the base in concentric relation to the pedestal and each condenser having a rotor shaft provided with a pinion, an annular dial member concentric with and rotatably mounted on the exterior of the pedestal at a point between the base and shade sections, a shaft extending downwardly from the dial and having the upper end operatively connected to the dial for actuation by the latter, a central driving gear supported for rotation in concentric relation to the pedestal and meshing with the pinions, and means operatively connecting the lower end of the shaft to the central driving gear for actuating the condensers simultaneously.

6. In a combined lamp and radio receiving apparatus, the combination of a base section having a pedestal extending upwardly therefrom and a shade section mounted on the pedestal at the upper end thereof, radio receiving apparatus having a rheostat supported in one of the sections and having a variable condenser located in the base section, a pair of annular dial members concentric with and independently turnably mounted on the exterior of the pedestal in spaced relation one above the other to occupy a location on the pedestal intermediate the base section and the shade section, a shaft extending downwardly from the dial members and having the upper end connected to one of the dial members for actuation by the latter, means operatively connecting the lower end of said shaft to the variable condenser, and means operatively connecting the other of said dial members to the rheostat.

7. In a combined lamp and radio receiving apparatus, the combination of a base section having a pedestal extending upwardly therefrom and a shade section mounted on the pedestal at the upper end thereof, radio receiving apparatus housed in the base, said apparatus including a rheostat and a variable condenser, a pair of annular dial members concentric with and independently turnably mounted on the exterior of said pedestal in spaced relation one above the other to occupy a location on said pedestal intermediate the base section and the shade section, a pair of shafts extending downwardly from the dial members, means connecting the upper end of one of the shafts to the uppermost dial member, means connecting the upper end of the other of the shafts to the lowermost dial member, and means connecting the lower ends of said shafts in actuating relation, one to said rheostat and the other to said variable condenser.

8. In a combined lamp and radio receiving apparatus, the combination of a base section hav-

ing a pedestal extending upwardly therefrom and a shade section mounted on the pedestal at the upper end thereof, radio receiving apparatus housed in the base section and including a plurality of variable condensers concentrically disposed with respect to the pedestal and each variable condenser having a rotor provided with a pinion, a central driving gear rotatably mounted about the axis of the pedestal and meshing with said pinions, an annular dial member concentric with and rotatably supported on the exterior of the pedestal at a point intermediate the base section and the shade section, a tubular shaft rotatable about the axis of the pedestal exteriorly of the latter and having the upper end connected to the dial member, and means connecting the lower end of the shaft to said central driving gear.

9. In a combined lamp and radio receiving apparatus, the combination of a base having a pedestal extending upwardly therefrom and a shade section mounted on the pedestal at the upper end thereof, radio receiving apparatus housed in the base section and including a rheo-

stat and a plurality of variable condensers concentrically disposed with respect to the pedestal and each condenser having a rotor provided with a pinion, a central driving gear rotatably supported about the axis of the pedestal and meshing with the pinions, a pair of annular dial members concentric with and independently turnably mounted on the exterior of said pedestal in spaced relation one above the other to occupy a location on the pedestal intermediate the base section and the shade section, a tubular shaft rotatable about the axis of the pedestal exteriorly of the latter and extending downwardly from the dial members, means operatively connecting the upper end of the shaft to one of the dial members and for operatively connecting the lower end of the shaft to the central driving gear, a second shaft mounted within the pedestal and having the upper end operatively connected to the other of the dial members, and means connecting the lower end of the second shaft to said rheostat.

DANIEL J. CROWLEY.
